TO FEDERAL PHOSPHORUS COMPANY, OF BIRMINGHAM, ALABAMA, A CORPORATION OF ALABAMA.

PROCESS FOR THE MANUFACTURE OF NEUTRAL SODIUM PHOSPHATE.

Application filed July 19, 1924. Serial No. 726,917.

This invention relates to a process for the manufacture of an alkali-metal phosphate and particularly to the manufacture of tri-sodium phosphate such as described in our 5 co-pending application No. 726,918.

The object of this invention is to produce a compound requiring in its manufacture less caustic than is now used in the manufacture of tri-sodium phosphate. It follows 10 that the material provided by our present process will contain less free caustic and be less injurious to fabrics and to individuals handling it.

According to the present practice, tri-sodium phosphate is generally manufactured 15 by the neutralization of sodium carbonate, which is commercially called soda ash, with phosphoric acid, whereby di-sodium phosphate is produced. After the production of 20 di-sodium phosphate it is causticized by the addition of caustic soda, thus converting the di-sodium phosphate into tri-sodium phosphate. The resultant tri-sodium phosphate solution is then cooled in a suitable manner 25 and solid tri-sodium phosphate separated out as a crystalline material. Based on the following chemical equations:

the theoretical quantities of materials necessary for the production of tri-sodium phosphate are as follows:

- 25.7 # H_3PO_4 per 100 # tri-sodium phosphate.
27.8 # Na_2CO_3 per 100 # tri-sodium phosphate.
40 10.5 # NaOH per 100 # tri-sodium phosphate.

Actual practice from several years' operation shows that in so far as the caustic is concerned this quantity is insufficient, and, 45 therefore, it appears that the material which is commercially called tri-sodium phosphate does not conform to the formula

- 50 but contains in addition NaOH , and the caustic soda necessary for crystallization of tri-sodium phosphate approaches nearer 15 # than the theoretical 10.5 # NaOH as given above. Extensive experiments were con-

ducted to determine if it were possible to 55 reduce the quantity of caustic necessary in tri-sodium phosphate manufacture as that element is both expensive and objectionable. During this investigation it was discovered that it was possible to produce tri-sodium 60 phosphate by the use of less caustic soda, and the resulting compound was neutral when titrated with a standard acid, using methyl orange as an indicator. The titration "ratio" varies from approximately 0.432 to 0.451, depending upon the concentration of the solution, a high "ratio" being used for higher concentrations. The necessary caustic is added to conform to the requirement as given in the 65 chemical equation as follows:

This caustic soda requirement or "ratio" may be judged by a method of control in 75 which the solution is titrated with a half normal hydrochloric acid solution using phenolphthalein and methyl orange as indicators. When the end point for the phenolphthalein is reached, a reading is made of the 80 acid used, and the titration is continued to a slight acid end point with the methyl orange. The reading of the titration of the phenolphthalein is then divided by the sum of the readings and a "ratio" of 0.432 to 85 0.451 is the desired resultant for the optimum conditions to produce the best yield of tri-sodium phosphate crystals when the solution is cooled. The "ratio" so determined is one means of deriving a constant as a measure 90 of the caustic present in the solution or crystals. Where the term "ratio" is used herein such method of determination is referred to.

In the preparation of neutral tri-sodium phosphate it was soon found that the presence 95 of sodium carbonate had a very great influence on the formation of neutral tri-sodium phosphate crystals. This influence was to keep tri-sodium phosphate in solution, as well as to reduce the P_2O_5 concentration in any given solution. In addition to keeping the tri-sodium phosphate in solution, the sodium carbonate caused the crystals which formed to be very 100 small, soft crystals. The yield was very low, with approximately 30% recovery of the tri-sodium phosphate as the highest when 4% sodium carbonate was present. A series of mixtures were made with tri-sodium phosphate 105

- and di-sodium phosphate and sodium carbonate with varying "ratios," and varying specific gravities, and the 30% yield referred to above was obtained from a solution having a "ratio" 5 of 0.409 in the solution and a specific gravity of 1.40 at 57° C. The liquor after the crystals were removed had a "ratio" of 0.375, and a specific gravity of 1.34; while a solution of the crystals in water had a "ratio" of 0.496. 10 This value for the crystals is very nearly what would be expected of pure neutral tri-sodium phosphate, *viz.*, 0.50.

If the sodium carbonate be absent, it is possible to crystallize neutral tri-sodium phosphate from a solution at 1.36 specific gravity at 90° C., and a ratio of 0.445, and get approximately 70% yield. As the specific gravity increases the "ratio" must also be increased to form neutral tri-sodium phosphate. 20 If the specific gravity is too high with respect to the "ratio" some di-sodium phosphate will be formed; while if the "ratio" is too high with respect to the specific gravity, there will be some alkaline tri-sodium found. 25

- The saturation curve E—F shown in the drawing will illustrate the necessity of varying the ratio with the specific gravity, and the crystallization area curves A—B and 30 C—D show within what area neutral tri-sodium phosphate can be produced. If the solutions be kept within the specified area N, there is no difficulty in producing tri-sodium phosphate corresponding to the formula

The production of this new compound by our process, offers distinct economic advantages over the manufacture of tri-sodium phosphate as produced at the present time, 40 and in addition to this economic feature, a tri-sodium phosphate containing no free alkali is produced which has distinct advantages for the consumer. The process and equipment of manufacture is similar to that carried on and used in the manufacture of alkaline tri-sodium phosphate. 45

A similar method of control is employed in alkaline tri-sodium phosphate operation, and the figures obtained usually vary between 50 0.53 and 0.55. These latter figures will approximate the result arrived at by the same method of testing the crystals formed from solutions having a titration ratio varying between 0.53 and 0.55, and the difference between 55 these titrations represents the excess of caustic in an alkaline tri-sodium phosphate over that produced by the herein described methods of manufacturing tri-sodium phosphate and indicates the excess of caustic present in the alkaline tri-sodium phosphate. After the tri-sodium phosphate solution is tested as described above, it is cooled in any suitable manner and the tri-sodium phosphate crystals separate out. 60 65 They may be dried in a centrifuge or any

other suitable means of de-watering, and then steam or air dried to remove the surface moisture. After drying, the crystals are ready for shipment.

In the manufacture of tri-sodium phosphate the operation is modified depending on the concentration of the acid used, in that when dilute acid is used to neutralize the sodium carbonate, it is necessary to concentrate the di-sodium phosphate or the tri-sodium phosphate solution before substantial recoveries may be made in the crystallization step. It is evident that if a sufficiently concentrated acid is used it is unnecessary to employ this concentration step inasmuch as the water 70 will be absent from the operation, and therefore the percentage of tri-sodium phosphate in the solution will be sufficiently high to permit removal of a substantial quantity of the crystals when the solution is cooled. Therefore, while dilute acid may be used in the manufacture of tri-sodium phosphate, it is preferable that a concentrated acid of approximately 60% H_3PO_4 be used to avoid the necessary evaporation step. If the di-sodium 75 phosphate is produced by roasting calcium phosphate with sodium acid sulphate, the resultant di-sodium phosphate may be treated in a manner similar to that described already. 80

The following proportions are given as illustrative of the proportions in making the above described tri-sodium phosphate by our process.

43# of 60% H_3PO_4 (25.8# H_3PO_4). 100
28# commercial soda ash (58% Na_2O).
11# caustic soda (76% Na_2O).

The acid is neutralized by the soda ash and any compounds such as iron, alumina, and calcium phosphates which are precipitated, are removed from the solution, preferably by filtration. The di-sodium phosphate solution is boiled prior to filtration in order that the carbon dioxide (CO_2) may be eliminated. After filtration caustic soda is added 105 and the solution thoroughly mixed. The mixture is then tested according to the previously outlined method and if sufficient caustic has not been added, an addition is made until the titration gives the desired figure; while if an excess of caustic has been added, di-sodium phosphate solution is added to reduce the figure to the desired point. The same equipment can be used for the 110 subsequent cooling, crystallization, de-watering and drying of this product as for the alkaline tri-sodium phosphate. 115 120

Having thus described our invention, what we claim as new and desire to secure by Letters Patent, is:—

1. The herein described process for the production of tri-sodium phosphate containing no free alkali which consists in providing a disodium phosphate solution substantially free of sodium carbonate, and adding caustic 125 130

soda to the solution until the resultant solution has a relation of the phenolphthalein titration to the methyl orange titration of .432 to .451.

5. 2. The process set forth in claim 1 in which the specific gravity of the solution is maintained above 1.30.

3. In a process of producing tri-sodium phosphate, the steps which comprise titrating the tri-sodium phosphate in solution us-

ing phenolphthalein and methyl orange as indicators and adding caustic soda to the tri-sodium phosphate solution until the relation of the phenol to the methyl orange titration is from .432 to .451.

In testimony whereof we affix our signatures.

CHARLES F. BOOTH.
ARTHUR B. GERBER.
